(57) **CLAIM**

The ornamental design for a water valve, as shown and described.

DESCRIPTION

FIG. 1 is a front, left and top perspective view of a water valve, showing my new design;

FIG. 2 is a front, left and top perspective view of the water valve in a detached state;

FIG. 3 is a front, left and top perspective view of the water valve in a detached state;

FIG. 4 is a front, left and top perspective view of the water valve in a detached state;

FIG. 5 is a front, left and top perspective view of the water valve in a detached state;

FIG. 6 is a front view thereof;

FIG. 7 is a rear view thereof;

FIG. 8 is a left side view thereof;

FIG. 9 is a right side view thereof;

FIG. 10 is a top plan view thereof;

FIG. 11 is a bottom plan view thereof; and,

FIG. 12 is an enlarged view of portion 12 of FIG. 5 thereof. The evenly broken lines depict unclaimed portions of the water valve; the dash-dot broken lines disclose unclaimed boundaries of the isolated and enlarged views; the broken lines form no part of the claimed design.

1 Claim, 12 Drawing Sheets
